UNITED STATES PATENT OFFICE.

CHARLES HENRY McCREADY, OF NEODESHA, KANSAS.

MACHINE FOR TURNING PIPES AND OTHER ARTICLES.

No. 823,804.

Specification of Letters Patent.

Patented June 19, 1906.

Application filed December 15, 1905. Serial No. 291,870.

To all whom it may concern:

Be it known that I, CHARLES HENRY McCREADY, a citizen of the United States, and a resident of Neodesha, in the county of Wilson 5 and State of Kansas, have invented a new and Improved Machine for Turning Pipes and other Articles, of which the following is a full, clear, and exact description.

The invention relates to machines for 10 screwing up and unscrewing pipes, tubes, and the like—such, for instance, as shown and described in the Letters Patent of the United States No. 614,333, granted to me November 15, 1898.

15 The object of the present invention is to provide a new and improved machine for turning pipes, screw-rods, and other articles in a very simple and convenient manner and allowing compensation for the longitudinal movement of the article unscrewed or screwed up.

The invention consists of novel features and parts and combinations of the same, which will be more fully described hereinafter and then pointed out in the claims.

25 A practical embodiment of the invention is represented in the accompanying drawings, forming a part of this specification, in which similar characters of reference indicate 30 corresponding parts in all the views.

Figure 1 is a plan view of the improvement as applied to a pipe. Fig. 2 is a sectional side elevation of the same on the line 2 2 of Fig. 1. Fig. 3 is an enlarged plan view of the 35 swivel connection between the jaws and the operating-lever for the same. Fig. 4 is a transverse section of the same. Fig. 5 is an enlarged side elevation of the joint for the sections of an operating-lever. Fig. 6 is a face 40 view of the same, parts being in section; and Fig. 7 is a perspective view of part of one of the jaws.

The pipe, screw-rod, or other article A to be turned for screwing or other purposes is 45 encircled by the flexible jaws B and B', pivotally connected at their ends with levers C and C', engaging at their free ends eyes D' and D'', secured to a ring D, mounted to turn on wheels or other bearings E, arranged on a 50 suitable base F. The ring D is adapted to be turned either by hand or power, for instance, by the use of an engine G, having its main shaft G' provided with a pinion G² in mesh with a gear-wheel D³, secured to or formed on 55 the under side of the ring D. Each of the le-

vers C and C' is made segmental in shape, as plainly indicated in Fig. 2, so that the ring D and the jaws B' are arranged in different parallel planes, and each of the levers C and C' is made in two sections C² C³, pivotally connected with each other at C⁴ and pressed on by a spring C⁵ engaging shoulders C⁶ of the section C² and C³. (See Figs. 2 and 5.) By this arrangement the sections C² and C³ are yieldingly connected with each other to compensate for the lengthwise movement of the article A when screwed up or unscrewed without changing the position of the base F and the wheel E, mounted to turn thereon.

The upper end of the lever C is preferably 70 provided with a swivel C', it being understood that each lever is fulcrumed at one end of a jaw and pivotally connected with the adjacent end of the other jaw—that is, as shown in Fig. 1, the lever C is fulcrumed on the angular link B² of the jaw B, while the lever C' is fulcrumed on the angular link B³ of the jaw B'. Each of the jaws B and B' is made of a plurality of links B⁴, pivotally connected with each other by bolts B⁵ to permit using more 80 or less links for each jaw to suit different sizes of pipes, screw-rods, or other articles to be operated upon.

When it is desired to turn the article A and the jaws B and B' encircle the article, as described and illustrated in Figs. 1 and 2, and a rotary motion is given to the ring D—say in the direction of the arrow a'—then the two levers C and C' draw the ends of the jaws B and B' toward each other, so as to cause the jaws 90 B and B' to close and firmly grip the article A. On the further turning of the ring D the links C and C' are carried bodily along, and as the links are connected with the jaws B and B' firmly gripping the article A it is evident that the article A is turned.

In order to permit convenient detachment of the jaws B and B' from the levers C and C', the end link B⁶ of the jaw B engages a removable pin C⁸ on the lever C', so that when this 100 pin is withdrawn the jaw B is readily disconnected from the lever C' to allow opening of the other jaw B' and consequent disengagement of both jaws from the article A. It is understood that when the article A is screwed 105 up or unscrewed, and consequently moves in the direction of its length, then the sections C² and C³ of each lever C and C' yield relatively to each other to allow of moving the article A a considerable distance in the direc- 110

tion of its length before it becomes necessary to change the position of the jaws B and B' on the article A for obtaining another grip.

The device is very simple and durable in construction, not liable to get easily out of order, and easily manipulated.

Having thus described my invention, I claim as new and desire to secure by Letters Patent—

- 10 1. A machine for turning pipes, screw-rods, and like articles, comprising jaws adapted to grip the article, levers comprising jointed sections having a limited angular movement with respect to each other and connected with the said jaws, and a ring mounted to turn and engaging the said levers.
- 20 2. A machine for turning pipes, screw-rods and like articles, comprising jaws adapted to grip the article, a lever fulcrumed on one jaw and connected with the other jaw, and a ring mounted to turn and engaging the said lever.
- 25 3. A machine for turning pipes, screw-rods and like articles, comprising flexible jaws adapted to encircle and grip the article, levers, each fulcrumed on one jaw and pivotally connected with the other jaw, and a ring mounted to turn and engaging the free ends of the said levers.
- 30 4. A machine for turning pipes, screw-rods and like articles, comprising flexible jaws adapted to encircle and grip the article, each jaw being formed of a plurality of removable links to permit the use of more or less links, according to the size of the article to be gripped, levers, each fulcrumed on one jaw and pivotally connected with the other jaw, and a ring mounted to turn and engaging the free ends of the said levers.
- 35 5. A machine for turning pipes, screw-rods and like articles, comprising flexible jaws adapted to encircle and grip the article, levers, each fulcrumed on one jaw and pivotally connected with the other jaw, each lever being segmental in form and made in sections yieldingly connected with each other, and means for operating the said levers in unison.
- 40 6. A machine for turning pipes, screw-rods

and like articles, comprising flexible jaws adapted to encircle and grip the article, levers having swivel ends pivotally connected with the adjacent ends of the jaws, and means for operating the said levers.

50 7. A machine for turning pipes, screw-rods and like articles, comprising flexible jaws adapted to encircle and grip the article, levers having swivel ends pivotally connected with the adjacent ends of the jaws, the levers being segmental in shape and made in sections yieldingly connected with each other to compensate for the movement of the article 60 in the direction of its length, and means for operating the said levers.

55 8. A machine for turning pipes, screw-rods and like articles, comprising flexible jaws adapted to encircle and grip the article, levers having swivel ends pivotally connected with the adjacent ends of the jaws, a ring connected with the free ends of the said levers, and a bearing for the said ring to turn on.

65 9. A machine for turning pipes, screw-rods and like articles, comprising flexible jaws adapted to encircle and grip the article, levers having swivel ends pivotally connected with the adjacent ends of the jaws, a ring connected with the free ends of the said levers, and a bearing for the said ring to turn on, the said jaws and ring lying in different 75 parallel planes.

70 10. A machine for turning pipes, comprising a ring mounted to turn, gripping-jaws offset vertically from the ring and coaxial therewith, and levers comprising jointed sections connecting the jaws and the ring, the sections of the levers having a limited angular movement with respect to each other whereby to 85 compensate for the movement of the jaws.

In testimony whereof I have signed my name to this specification in the presence of two subscribing witnesses.

CHARLES HENRY McCREADY.
